UNITED STATES PATENT OFFICE.

HARRY MANOTT AND JOHN HENRY McGRATH, OF MELBOURNE, VICTORIA, AUSTRALIA.

COMBINATION BED AND COUCH.

Application filed August 6, 1924, Serial No. 730,465, and in Australia May 3, 1924.

The object of the present invention is to provide as a composite article of furniture an improved combination bed and couch which includes a spring mattress and may be readily converted from its couch form to serve as a bed which will offer a maximum of comfort and repose to the user. The spring mattress is carried by a suitable frame or support which when in use as a bed is disposed horizontally above the seat portion of the couch and is capable of being swung upwardly and backwardly therefrom and retained in the latter position to form the back rest of the couch when the spring mattress is not required. Means are also provided whereby the bedding laid over the spring mattress in conventional manner is retained in proper position on said mattress when not in use despite the upward movement of the mattress with the bedding thereon. To effect this latter purpose the mattress frame is provided with end frames or members which swing downwardly against the bedding and are held in such position to keep the bedding in place whilst the mattress frame is in its upstanding position at the back of the couch.

Referring to the drawings which form part of this specification:—

Figure 1 is a front elevation of a convertible bed and couch constructed in accordance with the invention, the structure being shown in its couch form. A portion of the upholstery which covers the underside of the mattress frame is broken away for convenience of illustration.

Figure 2 is an end elevation looking from the left hand side of Figure 1 the spring mattress or couch back being indicated by broken lines in a horizontal position for sleeping purposes.

Figure 3 is a plan view of the convertible article showing the couch back or mattress in a horizontal position. End frames hinged to the mattress frame are seen in their folded positions in which they retain the bedding in position for use upon the spring mattress. A portion of this figure is broken away to show the adjacent part of the spring mattress and its supporting frame.

Figure 4 is a sectional end view showing the convertible article when in use as a bed.

Figure 5 is a part sectional front elevation showing the structure converted into a

bed. One of the end frames is indicated in a folded attitude by broken lines.

Figure 6 is a sectional end view of a convertible bed and couch embodying certain modifications. According thereto the couch is furnished with hinged arm rests which are swung outwardly and downwardly from their normal position preparatory to the lowering of the couch back or spring mattress. For convenience of illustration the bedding is removed from the mattress frame which is swung upwardly to form the couch back rest.

Figure 7 is a broken front elevation of the structure seen in Figure 6. The left hand part of the figure shows the spring mattress in a horizontal attitude for sleeping purposes, the adjacent arm rest of the couch being swung downwardly into an inoperative position. In the right hand part of the figure the spring mattress and the adjacent arm rest of the couch are seen in their raised positions.

Figure 8 is a fragmentary end view on an enlarged scale showing a fastening device for retaining the hinged end frames in a vertical position.

Figure 9 is a broken cross section on an enlarged scale of the spring mattress and its frame as shown in Figures 1 to 5.

According to the invention the improved convertible article includes a couch comprising a seat structure carrying a seat 2 and provided with suitable supporting legs or members 3 at each end. Transverse feet or base members 4 are provided at each end of the couch, these feet being adapted to rest upon the floor and being preferably provided with rearward extensions which project beyond the rear of the couch as at 5

in order to counterbalance the weight of the couch back rest when the latter is in an upstanding position as hereinafter described. Beneath the seat 2, the seat structure is preferably of box-like formation and to provide access to the compartment or compartments 7 formed by this box-like structure hinged or removable doors or panels 8 (Figures 1-5) may be provided. Or, if desired, the seat 2 may be hinged as at 9 (Figure 6) to the upper rear part of the box-like structure so that access may be had to the compartment 7 by raising the seat. Spring elements 11 may be fitted within the couch seat 2 which may be covered or upholstered as at

85

110

10 in any suitable manner. Arm rests 12 as seen in Figures 1 to 5 may also be provided at each end of the couch.

The member which forms the back rest 5 of the couch includes a mattress frame comprising longitudinal side members 13 and transverse end members 14. The said transverse members 14 of the mattress frame may carry apertured lugs or eyelets 15 adapted 10 to embrace hinge or pivot pins 16 which outstand from the seat structure of the couch adjacent its rear upper edge. The mattress frame may thus be swung from an upstanding position, where it forms the back 15 rest of the couch, into a horizontal position when required to convert the article into a bed. The mattress frame may be supported in such horizontal position by rests or stop members 17 disposed at each end of the 20 couch.

The spring mattress may be of the well known woven wire type as indicated at 18 in Figures 1-5 and is preferably attached at each end to cross bars 19 which are supported at each side of the mattress frame by suitable means such as brackets 21 preferably of right angle or L section, these brackets being secured to the longitudinal members or rails 13 of the mattress frame 25 at or adjacent the lower side thereof. The cross bars 19 are preferably of lesser height than the side rails 13 of the mattress frame and the brackets 21 are so arranged that the wire mattress 18 is stepped down or 30 disposed beneath the upper surface of the mattress frame so that the usual bedding indicated at 22 may be accommodated or partially accommodated within and beneath the upper surface of said frame. One of 35 the cross bars 19 is secured to its supporting brackets 21 whilst the other cross bar rests freely upon the corresponding brackets 21 and tension bolts 20 may pass through the last mentioned bar 19 and the adjacent transverse end member 14 of the mattress frame 40 as seen in Figure 5 whereby the tension of the wire mattress 18 may be adjusted according to requirements.

The hinged mattress frame is covered on 50 its front or underneath side by a suitable material such as fabric, leather or the like as indicated at 23 and such covering may be suitably padded or upholstered to provide a comfortable back rest when the article is 55 in use as a couch. This upholstered covering of the mattress frame thus hides the wire mattress 18 when the mattress frame is swung upwardly to form the couch backrest as seen in Figures 1 and 2.

60 Alternatively as seen in Figures 6 and 7 the spring mattress may be formed by coiled springs 28 arranged between the upholstered covering 23, which extends across the front or under side of the mattress frame, and a similar padded or upholstered mattress cov-

ering 24 which extends across the upper or rear side of the mattress frame. In this embodiment the bedding is laid upon the spring mattress covering 24 instead of the woven wire mattress 18 as previously mentioned. 70

Attached, preferably by hinges 32, to the mattress frame at each end thereof, are end members or frames 33 which are adapted to swing or fold inwardly towards each other in a plane at right angles to the mattress frame or couch back when the article is to be converted from its bed to its couch form. The end frames 33 may be thus laid flat against the bedding 22 at the rear or upper side of the mattress frame as shown in Figure 3 and in broken lines at the left of Figure 5 thereby retaining the bedding in its spread position upon the spring mattress 18 or 24 whilst the mattress frame is in its upstanding position as in Figures 1, 2 and 6. The end frames 33 may be of ornamental or other desired construction and when the article is in use as a bed they occupy a vertical position across each end of the bed as seen in Figures 4 and 5 and at the left of 7 so that the structure assumes the appearance of an ordinary bedstead. If desired distance pieces 34 may be interposed 95 between the mattress frame and the end frames 33 the latter being hinged to said distance pieces so that when said end frames are in their folded position they are spaced from the upper or rear side of the mattress frame members 13 thus affording greater depth to accommodate the bedding as indicated by broken lines at the left of Figure 5. 100

Any suitable means may be provided to retain the end frames 33 in both their folded and upright positions as above mentioned. By way of example the end frames may be secured in their folded position by a thumb screw or the like 36 which outstands from one of the frames 33 and passes through a slot 37 in an arm 38 which is hinged to the other end frame. To retain the end frames in their upright position a wedge or catch member 39 may be carried at one end of a stem or shank 41 which is mounted to turn 115 on the respective end frame and engages a corresponding wedge face or catch 42 formed on the underside of the adjacent arm rest 12. Or any other suitable form of catch for instance as indicated at 43 in Figure 7 may be employed to retain the end frames in their upright position. 120

In lieu of the fixed arm rests 12 shown in Figures 1 to 5, the couch may be provided with hinged arm rests 46 which may be padded or upholstered as shown in Figures 6 and 7. The hinges 47 of these arm rests are attached to the ends of the couch seat structure with their axes transversely of the couch similarly to the hinges of the end frames 33. The arm rests 46 are thus ca- 125 130

pable of being swung outwardly and downwardly from their normal position as seen in Figure 6 and at the right hand side of Figure 7 into an out of the way position as shown at the left hand side of Figure 7. The spring mattress frame or back rest, which is prevented from inadvertently swinging forwardly and downwardly about its axis 16, by the hinged arm rests 46 when the latter are in their upright position, may then be lowered into a horizontal position for use as a bed. In this example the cross members 14 of the mattress frame may rest upon the top of the seat structure or legs 3 so that the mattress extends for substantially the full length of the couch seat and part of this length may be occupied by the upholstered arm rests when the latter are in position for use. Any suitable fastening means or devices such for instance as pins 48 adapted to enter coinciding holes 49 in the hinged arm rests and the seat structure, may be provided to hold said arm rests in their raised position.

To convert the article from a couch into a bed the mattress frame is swung forwardly and downwardly about its pivotal or hinging point 16 so that it assumes a substantially horizontal position above the couch seat 2. If the couch is provided with upholstered and hinged arm rests 46 as aforesaid such members are swung downwardly about their hinges 47 preparatory to lowering the mattress frame or couch back. The end frames 33 are then released and swung upwardly into a vertical position which permits the usual pillows and bolster, indicated by broken lines in Figures 4 and 5, to be placed upon the bedding 22 which is retained in spread position on the spring mattress by the end frames 33 when the mattress is in its inoperative or upstanding position as aforesaid.

To convert the bed into a couch the pillows and bolster may be removed and placed in the aforesaid compartment or compartments 7 formed within the seat structure beneath the couch seat 2. The end frames 33 are then folded inwardly and fastened in such posi-

tion by the aforesaid screw 36 and arm 38 50 or other suitable means so that they press upon the bed clothes and retain them and the bedding 22 securely to the mattress. The mattress frame is then swung upwardly and rearwardly into its raised position 55 whereupon the article is ready for use as a couch the spring mattress and bedding 22 being entirely hidden from view by the covering material or upholstery 23 on the front or underneath face of the mattress frame. 60 The hinged arm rests 46 (if provided) are finally moved upwardly about their hinges 47 and locked in their upright position by the fastening means 48, as aforesaid. The rearward extensions 5 of the couch feet 4 65 serve to effectively counterbalance the weight of the raised mattress frame and thus prevent the couch from tipping backwardly.

Having now described our invention what we claim as new and desire to secure by 70 Letters Patent is:—

In a convertible bed and couch, a couch body having upstanding arms at its ends, each arm including a hand rail, and a back including an open frame pivotally mounted 75 between said arms and adapted to be swung from an upright position at the back of the couch body to a lowered position resting thereon between the arms, upholstery covering the front of said frame, a spring mounted in said frame and adapted to support a mattress in the rear portion of the frame, and members pivoted to said frame and adapted to be swung from an upright to a lowered position in overlying relation to the 80 frame and a mattress carried thereby, latch rods rotatably carried by said end members and having upper and lower arms and adapted to be rotated by the upper arms to move the lower arms into and out of position to 85 engage beneath the hand rails of said arms and retain the end members elevated, and means to releasably secure the end members lowered.

In testimony whereof we affix our signatures.

HARRY MANOTT.
